Specification for Design.

Patented Aug. 10, 1920.

Application filed December 9, 1918. Serial No. 266,000. Term of patent 14 years.

To all whom it may concern:

Be it known that we, WILLIAM E. DE RICHELIEU and AUREA D. WAGNER, citizens of the United States, residing at Philadelphia, in the county of Philadelphia and State of Pennsylvania, have invented a new and original and ornamental Design for a Label for Poison-Bottles, of which the following is a specification, reference being had to the accompanying drawing, forming a part thereof.

Fig. 2 is a vertical section through the label as shown in Fig. 1.

We claim:

The ornamental design for a label for poison-bottles, as shown.

WILLIAM E. DE RICHELIEU.
AUREA D. WAGNER.
